(57) **CLAIM**

The ornamental design for a pet toy, as shown and described.

DESCRIPTION

FIG. 1 is a front elevational view of a pet toy showing my new design;

FIG. 2 is a rear elevational view thereof;

FIG. 3 is a left side view thereof;

FIG. 4 is a right side view thereof, shown in an enlarged scale;

FIG. 5 is a top plan view thereof, shown in an enlarged scale;

FIG. 6 is a bottom plan view thereof;

FIG. 7 is a bottom, front and left side perspective view thereof;

FIG. 8 is a bottom, rear and right side perspective view thereof;

FIG. 9 is a bottom, front and left side perspective view with the internal component removed;

FIG. 10 is a bottom, front and right side perspective view with the internal component removed;

FIG. 11 is a top, front, left side perspective view with the internal component removed;

FIG. 12 is a front elevational view of the internal component;

FIG. 13 is a rear elevational view of the internal component;

FIG. 14 is a left side view of the internal component;

FIG. 15 is a right side view of the internal component;

FIG. 16 is a top plan view of the internal component;

FIG. 17 is a bottom plan view of the internal component;

FIG. 18 is a bottom, front and left side perspective view of the internal component; and,

FIG. 19 is a bottom, rear and right side perspective view of the internal component.

The broken lines depict environmental subject matter and form no part of the claimed design.

1 Claim, 14 Drawing Sheets
